EUGÈNE PETIT.

UNITED STATES PATENT OFFICE.

EUGÈNE PETIT, OF PARIS, FRANCE, ASSIGNOR TO ALEXANDER SMITH & SONS CARPET COMPANY, OF YONKERS, NEW YORK.

DESIGN FOR A CARPET.

SPECIFICATION forming part of Design No. 13,707, dated March 6, 1883.

Application filed January 17, 1883. Term of patent 3½ years.

To all whom it may concern:

Be it known that I, EUGÈNE PETIT, of the city of Paris, France, have invented or produced a new and original Design for a Pattern to be 5 Inwrought into Moquette and other Carpeting, similar to the photographs accompanying this specification; and I do hereby declare that the photographs accompanying this specification do give and convey to any one skilled in the 10 art of carpet-weaving a defined and thorough description of the nature of my invention, and are sufficient to enable any one skilled in the art of carpet-weaving to use my invention.

What I claim as my invention, and desire to secure by Letters Patent, is—

The design hereunto annexed, when applied to carpeting in the form similar to the photographs accompanying this specification.

EUGÈNE PETIT.
